(57) **CLAIM**

The ornamental design for a call box, as shown and described.

DESCRIPTION

FIG. 1 is an elevated front left perspective view of an embodiment of a call box, with broken, phantom lines

indicating a lowered cover for a front of the call box, a spacer for a rear of the call box, and a recessed area of the front of the call box;

FIG. 2 is an elevated front left perspective view of the call box of FIG. 1, with broken, phantom lines indicating a raised cover for a front of the call box, a spacer for a rear of the call box, and a recessed area of the front of the call box;

FIG. 3 is a front plan view of a call box, with broken, phantom lines indicating a lowered cover for a front of the call box;

FIG. 4 is a rear view of a call box, with broken, phantom lines indicating a lowered cover for a front of the call box and a spacer for a rear of the call box and a recessed area of the front of the call box;

FIG. 5 is a right side plan view of a call box, with broken, phantom lines indicating a lowered cover for a front of the call box and a spacer for a rear of the call box;

FIG. 6 is a left side plan view of a call box, with broken, phantom lines indicating a lowered cover for a front of the call box and a spacer for a rear of the call box;

FIG. 7 is an end or bottom plan view of a call box, with broken, phantom lines indicating a lowered cover for a front of the call box and a spacer for a rear of the call box;

FIG. 8 is an top plan view of a call box, with broken, phantom lines indicating a lowered cover for a front of the call box and a spacer for a rear of the call box;

FIG. 9 is a front plan view of a call box, with broken, phantom lines indicating a raised cover for a front of the call box and a recessed area of the front of the call box;

FIG. 10 is a right side plan view of a call box, with broken, phantom lines indicating a raised cover for a front of the call box and a spacer for a rear of the call box;

FIG. 11 is a left side plan view of a call box, with broken, phantom lines indicating a raised cover for a front of the call box and a spacer for a rear of the call box;

FIG. 12 is an end or bottom plan view of a call box, with broken, phantom lines indicating a raised cover for a front of the call box and a spacer for a rear of the call box;

FIG. 13 is an top plan view of a call box, with broken, phantom lines indicating a raised cover for a front of the call box and a spacer for a rear of the call box;

FIG. 14 is an elevated front left perspective view of a further embodiment of a call box, with broken, phantom lines

(Continued)

indicating a lowered cover for a front of the call box, a spacer for a rear of the call box, and a recessed area of the front of the call box;

FIG. 15 is an elevated front left perspective view of the further embodiment of a call box, with broken, phantom lines indicating a raised cover for a front of the call box, a spacer for a rear of the call box, and a recessed area of the front of the call box;

FIG. 16 is a front plan view of the further embodiment of a call box, with broken, phantom lines indicating a lowered cover for a front of the call box;

FIG. 17 is a rear view of the further embodiment of the call box, with broken, phantom lines indicating a lowered cover for a front of the call box and a spacer for a rear of the call box and a recessed area of the front of the call box;

FIG. 18 is a right side plan view of the further embodiment of the call box, with broken, phantom lines indicating a lowered cover for a front of the call box and a spacer for a rear of the call box;

FIG. 19 is a left side plan view of the further embodiment of the call box, with broken, phantom lines indicating a lowered cover for a front of the call box and a spacer for a rear of the call box;

FIG. 20 is an end or bottom plan view of the further embodiment of the call box, with broken, phantom lines indicating a lowered cover for a front of the call box and a spacer for a rear of the call box;

FIG. 21 is an top plan view of the further embodiment of the call box, with broken, phantom lines indicating a lowered cover for a front of the call box and a spacer for a rear of the call box;

FIG. 22 is a front plan view of the further embodiment of the call box, with broken, phantom lines indicating a raised cover for a front of the call box and a recessed area of the front of the call box;

FIG. 23 is a right side plan view of the further embodiment of the call box, with broken, phantom lines indicating a raised cover for a front of the call box and a spacer for a rear of the call box;

FIG. 24 is a left side plan view of the further embodiment of the call box, with broken, phantom lines indicating a raised cover for a front of the call box and a spacer for a rear of the call box;

FIG. 25 is an end or bottom plan view of the further embodiment of the call box, with broken, phantom lines indicating a raised cover for a front of the call box and a spacer for a rear of the call box; and,

FIG. 26 is an top plan view of the further embodiment of the call box, with broken, phantom lines indicating a raised cover for a front of the call box and a spacer for a rear of the call box.

In the drawings, the dash-dash broken lines illustrate portions of the call box that form no part of the claimed design. The dot-dot-dash broken lines depict environmental subject matter and form no part of the claimed design.
